Application October 17, 1944, Serial No. 559,085

12 Claims. (Cl. 121—19)

1

This invention relates to pressure fluid motors and more particularly to improvements in the fluid distribution means of a pressure fluid motor of the reciprocating piston type.

An object of the present invention is to provide an improved pressure fluid motor. Another object is to provide an improved pressure fluid motor having improved fluid distribution means. A further object is to provide an improved distributing valve mechanism for a pressure fluid motor. A still further object is to provide an improved fluid distributing valve mechanism embodying cooperating relatively movable fluid distributing valves for controlling the flow of pressure fluid to the motor cylinder in an improved manner. Another object is to provide an improved valve guiding arrangement whereby both valves are slidably guided at their inner and outer peripheries. Yet another object is to provide an improved valve mechanism embodying cooperating relatively movable fluid distributing valves having a novel passage arrangement associated therewith whereby an extremely sensitive valve action is attained, resulting in improved motor operation. These and other objects and advantages of the invention will, however, hereinafter more fully appear.

In the accompanying drawings there are shown for purposes of illustration two forms which the invention may assume in practice.

In these drawings:

Fig. 1 is a view in longitudinal vertical section, with parts broken away, through a pressure fluid motor constructed in accordance with a preferred illustrative embodiment of the invention.

Figs. 2 and 3 are sectional views similar to Fig. 1, showing the fluid distributing valves and motor piston in different operating positions.

Fig. 4 is an enlarged fragmentary sectional view taken on the plane of Fig. 1, showing the fluid distributing valves and associated passages.

Fig. 5 is a perspective view of the front distributing valve.

Fig. 6 is a longitudinal vertical sectional view, with parts broken away, through a pressure fluid motor illustrating another embodiment of the invention.

Figs. 7 and 8 are sectional views similar to Fig. 6, showing the fluid distributing valves and motor piston in different operating positions.

Fig. 9 is an enlarged fragmentary sectional view taken on the plane of Fig. 6, showing the fluid distributing valves and associated passages.

Fig. 10 is a side elevational view of the rear distributing valve shown in Fig. 6.

Fig. 11 is an elevational view of the valve shown in Fig. 10.

In the illustrative embodiment of the inven-

2

tion shown in Figs. 1 to 5, inclusive, there is a motor cylinder 1 having a bore 2 containing a reciprocating hammer piston 3. The cylinder has a rear head 4 and a front head 5, and the piston has a piston head 6 fitting the cylinder bore and a reduced forward extension 7 guided in a bore 8 in the front head. Arranged in axial alignment with the cylinder bore at the rear end of the cylinder is an enlarged bore 9 in which the rear cylinder head is received, and arranged in the bore 9 at the rear of the head 4 is the improved fluid distributing valve mechanism, generally designated 10. This valve mechanism includes a valve box 11 received in the bore 9 at the rear side of the rear cylinder head in engagement with the latter, and also arranged in the bore 9 is a rear valve box cover 12. An annular member 13 is arranged in the bore 9 between the valve box cover and a member 14. A rear head block 15 abuts the rear face of the member 14 for clamping the parts 4, 11, 12 and 13 in position within the bore 9. The valve box 11 has aligned end valve receiving bores 16 and 17 connected by a reduced bore 18 in an intermediate inwardly directed annular portion 19 of the valve box. The rear cylinder head 4 has a rearwardly projecting cylindrical portion 20 extending centrally through the bores 17, 18, 16 with its external surface concentric therewith, and this projecting portion has a reduced rear end 21 fitting in a bore 22 in the valve box cover 12. Surrounding the forward portion of the projection 20 is a front annular groove 23, and the valve box cover 12 has a rear recess 24 in its forward side surrounding the reduced portion 21 and connected by parallel longitudinal passages 25 with the groove 23. Formed in the valve box at its opposite ends are annular chambers 26 and 27 with which the bores 16 and 17 respectively communicate at their outer sides. The chamber 26 is connected by a fluid conducting passage 28 in a cylinder wall with the front end of the cylinder bore, while the chamber 27 is connected by fluid conducting passages 29 in the rear cylinder head with the rear end of the cylinder bore.

In this improved construction, reciprocable in the valve box bores are cooperating relatively movable fluid distributing valves 30 and 31 of generally L-shape in cross section. These valves have sleeve-like bodies 32 and 33 respectively, arranged in telescopic relation. The rear valve 30 has an internal annular rear flange 34, while the front valve 31 has an external annular front flange 35. The exterior periphery of the body of the rear valve 30 is slidably guided in the rear bore 16, while the exterior surface of the external valve flange 35 is slidably guided in the front bore 17. The exterior surface of the

sleevelike body of the front valve 31 slidably engages the intermediate reduced bore 18, while the inner periphery of the internal annular flange 34 on the rear valve slidably engages the exterior surface of the cylindrical projection 20. The inner peripheral surface of the body of the front valve 31 is also slidably guided on the exterior periphery of the projection 20, and the sleevelike body 33 of the front valve is slidably arranged within the sleevelike body of the rear valve. The front valve 31 has formed on the rear or inner end of its body spaced projections 36 (Fig. 5) which are engageable with the forwardly facing inner surface of the internal annular flange 34 of the rear valve. The cylinder head 4 and the valve box cover 12 have formed thereon at their inner surfaces annular projections 37 and 38 located at the opposite ends of the valve chamber, and the inwardly facing surfaces of these projections provide seats against which the opposite outer ends of the valves respectively abut. The passages 25 are continuously connected by passages 39 with the space between the rear end surface of the body of the front valve and the front surface of the internal flange of the rear valve, so that these surfaces are continuously subjected to the action of pressure fluid. A restricted passage 40 connects the annular space 26 with the valve box bore 17, while a similar restricted passage 41 connects the space 21 with the valve box bore 16. Fluid under pressure may be supplied to the distributing valve mechanism 10 through the bore of a throttle valve 42 rotatably mounted within the rear head block, and a port 43 in the valve connects the valve bore with a passage 44 communicating with an annular space 45 in the member 14. The space 45 is connected through ports 46 and the interior of the annular member 13 to an annular space 47 in the rear face of the valve box cover 12, and ports 48 connect the space 47 with the recess 24.

Disposed substantially midway between the ends of the cylinder bore 2 is a piston controlled cylinder exhaust passage 49. A valve throwing passage 50 is connected by a port 51 with the valve box bore 17 at the rear or inner face of the external flange 35 of the front valve 31, and by a port 52 with the cylinder bore at a point a small distance rearwardly of the cylinder exhaust passage 49. A second valve throwing passage 53 is connected by a port 54 with the valve box bore 16 at the front or inner end of the body of the rear valve 30 and by a port 55 with the cylinder bore a slight distance forwardly of the cylinder exhaust passage 49. Since the passages 38 are relatively restricted and the fluid may flow relatively freely past the outer ends of the valves when the latter are unseated and due to the expansion of the fluid flowing past the outer ends of the valves, the pressure of the fluid at the outer ends of the valves is relatively lower than the substantially line pressure within the space between the rear end of the front valve and the forwardly facing surface of the internal flange of the rear valve, so that when pressure fluid is supplied to the throwing passages 50 and 53 the valves may be thrown toward their seated, closed positions as will later be made apparent.

The mode of operation of the improved pressure fluid motor of the embodiment of the invention above described is as follows: When the throttle valve 42 is turned into the position 75

shown, pressure fluid may flow from the valve bore through port 43, passage 44, annular space 45, passage 46, through the annular member 13 and recess 47, and through passages 48 to the recess 24, and thence through passages 25 to the annular groove 23. When the parts are in the position shown in Figs. 1 and 4, pressure fluid may flow from the front supply groove 23 past the front face of the front valve 31 and through the fluid conducting passages 29 to the rear end of the cylinder bore at the rear side of the piston head of the motor piston, the pressure fluid acting on the rear pressure area of the piston head to move the piston forwardly. Concurrently, the front end of the cylinder bore at the front side of the piston head is connected to the exhaust through the exhaust passage 49. The rear end of the bore 17 at the rear side of the external flange 35 of the front valve 31 is likewise connected to exhaust through the throwing passage 50. The front valve 31 is at this time held in its rearmost position by the pressure fluid acting on the effective front pressure area of the valve, and the latter, due to the engagement of the projections 36 with the front face of the internal flange 34, serves to hold the rear valve in its closed position against the annular seat 37. As the motor piston moves forwardly from the position shown in Fig. 1, the leading edge of the piston first overruns the port 52 of the throwing passage 50 and thereafter the leading edge of the piston head overruns the exhaust passage 49, thereby cutting off communication of the front end of the cylinder bore 35 with the exhaust; and upon continued forward piston movement the leading edge of the piston head overruns the port 55 of the throwing passage 53. Thereafter the following edge of the piston head uncovers the port 52 of the throwing passage 50, admitting pressure fluid from the rear end of the cylinder bore through the throwing passage 50 and port 51 to the bore 17 at the rear side of the external flange 35 of the front valve 31. Due to the relatively free flow of fluid past the front face of the front valve to the rear end of the cylinder bore and the expansion of the fluid in the rear end of the cylinder bore as a result of forward piston movement, the pressure due to the fluid acting on the effective front pressure area of the front valve, while still substantially greater than the opposing pressure at the rear end of the valve, is sufficiently reduced with respect to such opposing pressure so that when the throwing passage 50 is opened, the front valve is quickly thrown forwardly to its closed position against its annular seat 38, as shown in Fig. 2. The rear valve 30 is maintained in its rearmost closed position by the fluid acting on the front face of the internal flange 34. When the valves are both held closed against their seats, as shown in Fig. 2, flow of pressure fluid to both ends of the cylinder bore is momentarily completely cut off and forward movement of the piston continues under the expansive action of the fluid in the rear end of the cylinder bore and momentum. When the following edge of the piston head uncovers the exhaust passage 49, the rear end of the cylinder bore is connected to exhaust, thereby causing a sudden drop in the pressure acting on the front end of the body of the rear valve 30 through the restricted passage 41, and, as a result, the live pressure fluid acting on the effective rear pressure area of the rear valve throws the rear valve forwardly into its open

position shown in Fig. 3. As soon as the rear valve leaves its seat 37, its entire rear pressure area is subjected to live pressure fluid so that the rear valve is sharply thrown into its foremost position. The fluid trapped in the front end of the cylinder bore in advance of the piston head is highly compressed by the piston as the latter approaches the end of its forward travel, and this compression pressure serves to cushion the piston at the forward end of its travel. When the parts are in the position shown in Fig. 3, pressure fluid may flow from the rear supply recess 24 past the rear face of the rear valve and through the annular space 26 and fluid conducting passage 28 to the front end of the cylinder bore at the front side of the piston head, the pressure fluid acting on the forward pressure area of the piston head moving the piston rearwardly. Concurrently, the rear end of the cylinder bore at the rear side of the piston head is connected to the exhaust through the exhaust passage 49. The rear valve 38 is at that time held in its forward position by the pressure fluid acting on the effective rear pressure area of the valve, and the latter, due to the abutting engagement of the internal flange 34 with the projections 36 on the front valve, acts to maintain the front valve in its closed position against its seat 38. As the motor piston moves rearwardly from the position shown in Fig. 3, the leading edge of the piston head first overruns the exhaust passage 49, thereby cutting off communication of the rear end of the cylinder bore with the exhaust; and upon continued rearward piston movement the leading edge of the piston head overruns the port 52 of the throwing passage 50, and thereafter the following edge of the piston head uncovers the port 55 of the throwing passage 53, admitting pressure from the front end of the cylinder bore through the throwing passage 53 and port 54 to the bore 16 at the forward side of the front end of the body of the rear valve 38. Due to the relatively free flow of fluid past the rear face of the rear valve to the front end of the cylinder bore and the expansive action of the fluid in the front end of the cylinder bore as a result of rearward piston movement, the pressure due to the fluid acting on the effective rear pressure area of the rear valve, while still greater than the pressure due to the fluid acting on the front face of the internal flange 34, is sufficiently reduced with respect to the latter pressure so that when the throwing passage 53 is opened the rear valve is quickly thrown rearwardly to its closed position against its seat 37, as shown in Fig. 1. The front valve is maintained against its seat 38 by the pressure of the fluid acting on the rear end of the sleeve-like body 33 of the front valve. As the piston continues to move rearwardly, its following edge uncovers the exhaust passage 49 so that the front end of the cylinder bore is connected to exhaust, causing a sudden drop in pressure of the fluid acting on the rear face of the external flange 35 of the front valve through the restricted passage 48, and, as a result, the live pressure fluid acting on the effective front pressure area of the front valve throws the front valve rearwardly into its open position shown in Fig. 1. As soon as the front valve leaves its seat, the entire front pressure area of the front valve is made effective so that the front valve is sharply thrown into its rearmost position. The rear valve is

maintained in its rearmost seated position by the projections 36 on the front valve abutting the front face of the internal flange 34. The fluid trapped in the rear end of the cylinder bore rearwardly of the piston head is compressed by the piston as it approaches the end of its rearward travel, and this compression pressure serves to cushion the piston at the rearward end of its travel. The sequence of events above described is rapidly repeated during normal operation of the motor.

In the embodiment of the invention shown in Figs. 6 to 11 inclusive, the motor structure is essentially the same as that above described with the main exception that the fluid distribution means is somewhat modified. In this construction, the annular portion 19 provided with the reduced bore between the valve box bores 16 and 17 is omitted and the valves are provided with compression areas so that the same are thrown into open position by compression pressure. As in the preferred embodiment, the motor cylinder 1 has a bore 2 containing a reciprocatory motor piston 3. The motor cylinder has a rear cylinder head 60 similar to the rear head 4, and a front cylinder head 5. The cylinder head 60 is arranged in a bore 9 at the rear end of the cylinder bore, and abutting the rear surface of the cylinder head and the bore 9 is a valve box 61 having a rear cover 62. The rear cylinder head has a cylindrical portion 63 projecting rearwardly therefrom through the valve box in a manner similar to the projecting portion 20 of the head 4 of the preferred embodiment. The rear recess 24, passages 25 and front annular groove 23 are the same as those in the first embodiment. The valve box has end recesses 64 and 65, and a portion 66 intermediate these recesses is formed with a bore 67. Formed in the walls of the bore 67 is an annular groove 68. The inner adjacent surfaces of the end valve box cover and rear cylinder head are plane at 69 and 70 respectively. Reciprocably mounted in the valve box is a pair of cooperating relatively movable, fluid distributing valves 71 and 72 having sleeve-like bodies 73 and 74 respectively, arranged in telescopic relation. The front valve 72 has an external annular flange 75 slidably engaging at its external periphery the walls of the bore 67, and the inner periphery of the valve body 74 slidably engages the exterior periphery of the rear head projection 63. The rear valve 71 has an internal annular flange 76 slidably engaging the exterior periphery of the projection 63 and the exterior surface of the rear valve body 73 slidably fits the bore 67. The exterior surface of the body 74 of the front valve slidably fits the inner surface of the rear valve body 73. The rear valve 71 has at its front or inner end spaced projections 77 which are abuttingly engageable with the rear or inner face of the external flange 75 of the front valve. Ports 39 connect the passages 25 with the spaces between the rear end of the front valve body and the front face of the internal flange of the rear valve. The valves have oppositely facing outer surfaces 78 and 79 which are subjectable to compression pressure. Projecting outwardly in opposite directions away from the valve flanges at the remote ends of the valves are annular portions 80 and 81 respectively which are adapted to seat against the plane inwardly facing surfaces 69 and 70 respectively of the valve box cover and rear cylinder head. A fluid conducting passage 28 connects the rear valve box recess 64 with the front end

of the cylinder bore, while fluid conducting passages 29 connect the front valve box recess 65 with the rear end of the cylinder bore. A throwing passage 82 is connected by a port 83 with the annular groove 68 which communicates with the space between the front end of the rear valve 11 and the rear or inner face of the external flange 75 of the front valve 72, and communicating with the cylinder bore at longitudinally spaced points respectively located slightly to the rear of and slightly in advance of the cylinder exhaust passage 49 are ports 84 and 85 for connecting the throwing passage of the cylinder bore. As in the first embodiment, since the passages 38 are relatively restricted and the fluid may flow relatively freely past the outer ends of the valves when the latter are unseated and due to the expansive action of the fluid, the pressure of the fluid at the outer ends of the valves is relatively lower than the substantially line pressure in the internal space between the valves, so that when pressure fluid is supplied to the throwing passage 82 the valves may be thrown toward their seated, closed positions as hereinafter described.

The mode of operation of this modified embodiment of the invention is as follows: When the parts are in the position shown in Figs. 6 and 9, pressure fluid may flow from the front supply groove 23 through the valve chamber past the forward face of the front valve and through the fluid conducting passages 29 to the rear end of the cylinder bore at the rear side of the motor piston, the pressure fluid acting on the rear pressure area of the piston head 6 to move the piston forwardly. Concurrently, the front end of the cylinder bore at the front side of the piston head is connected to exhaust through the exhaust passage 49. The front valve 72 is at this time held in its rearmost position by the pressure fluid acting on the effective front pressure area of the valve, and the latter, due to the abutting engagement of its external flange 75 with the projections 71 on the rear valve 11 acts to hold the rear valve in its closed position against the front face 69 of the valve box cover. As the motor piston moves forwardly from the position shown in Fig. 6, the leading edge of the piston head first overruns the port 84 of the throwing passage 82, and thereafter the leading edge of the piston head overruns the exhaust passage 49, thereby cutting off communication of the front end of the cylinder bore with exhaust; and upon continued forward piston movement the leading edge of the piston head overruns the port 85 of the throwing passage 82, and thereafter the following edge of the piston head uncovers the port 84 of the throwing passage 82, thereby admitting pressure fluid from the cylinder bore through the throwing passage to the port 83 and groove 68, the pressure fluid acting on the rear surface of the external flange 75 of the front valve to throw the latter forwardly into its closed position shown in Fig. 7. Due to the relatively free flow of fluid past the front face of the front valve to the rear end of the cylinder bore and the expansion of fluid in the rear end of the cylinder bore due to the forward piston movement, the pressure of the fluid acting on the effective rear pressure area of the front valve is substantially greater than the pressure at the front face of the valve so that when the throwing passage is opened, the front valve is quickly thrown forwardly into its closed position. The rear valve is maintained in its rearmost closed position by the fluid acting on the front face of the internal flange 16. When

the valves are both held closed, as shown in Fig. 7, the flow of pressure fluid to both ends of the cylinder bore is momentarily completely cut off and forward movement of the piston continues under the expansive action of the fluid in the rear end of the cylinder bore and momentum. When the following edge of the piston head overruns the exhaust passage 49, the rear end of the cylinder bore is connected to exhaust. As the motor piston approaches the end of its travel, the fluid trapped in the front end of the cylinder bore is highly compressed, and this compression pressure is transmitted through the passage 28 to the rearwardly facing pressure area 78 on the rear valve, and this compression pressure, together with the live pressure fluid acting on the rear surface of the internal valve flange 16, acts to throw the rear valve forwardly from its closed position, shown in Fig. 7, to its open position shown in Fig. 8. The fluid trapped in the front end of the cylinder bore in advance of the piston head serves to cushion the piston at the forward end of its travel. When the parts are in the position shown in Fig. 8, pressure fluid may flow from the rear recess 24 through the valve chamber past the rear face of the rear valve and through passage 28 to the front end of the cylinder bore at the front side of the piston head, the pressure fluid acting on the pressure area of the piston head to move the piston rearwardly. Concurrently, the rear end of the cylinder bore at the rear side of the piston head is connected to exhaust through the exhaust passage 49. The rear valve 11 is at that time held in its forward position by the pressure fluid acting on the rear pressure area of the valve, and the latter, due to the abutting engagement of the projections 71 with the rear face of the external flange 75 of the front valve, acts to maintain the front valve in closed position against the rear surface 70 of the rear cylinder head. As the motor piston moves rearwardly from the position shown in Fig. 8, the leading edge of the piston head first overruns the exhaust passage 49, thereby cutting off communication of the rear end of the cylinder bore with the exhaust; and upon continued rearward piston movement the leading edge of the piston head overruns the port 84 of the throwing passage 82, and thereafter the following edge of the piston head uncovers the port 85 of the throwing passage 82, admitting pressure fluid from the front end of the cylinder bore through the throwing passage 82 and port 83 to the groove 68 to act on the front pressure area of the rear valve 11. Due to the relatively free flow of fluid past the rear face of the rear valve to the front end of the cylinder bore and the expansion of fluid in the front end of the cylinder bore, due to rearward piston movement, the pressure of the fluid acting on the effective front pressure area of the rear valve is substantially greater than the pressure at the rear face of the valve so that when the throwing passage 82 is opened, the rear valve is quickly thrown rearwardly to its closed position. The front valve is maintained in its closed position by the fluid acting on the rear end of the valve body. When both of the valves are held in closed position, the flow of fluid to both ends of the cylinder bore is momentarily completely cut off and the motor piston continues to move rearwardly by the expansive action of the fluid in the front end of the cylinder bore and momentum. As the piston continues to move rearwardly, the following edge of the piston head overruns the exhaust passage

48 connecting the front end of the cylinder bore to exhaust; and upon continued rearward movement the fluid trapped in the rear end of the cylinder bore is highly compressed, and this compression pressure acts on the forwardly facing pressure area 79 of the front valve to throw the latter rearwardly into its open position shown in Fig. 6. The fluid trapped in the rear end of the cylinder bore cushions the piston at the rearward end of its travel. The sequence of events above described are rapidly repeated during normal operation of the motor.

As a result of this invention an improved pressure fluid motor is provided having improved fluid distribution means, whereby fluid is supplied to the motor cylinder in an improved manner resulting in more efficient motor operation. It will further be evident that by the provision of the cooperating relatively movable fluid distributing valves, one valve controlling the flow of pressure fluid to each end of the cylinder, the valve action of the motor is materially improved. Also by the provision of the improved valve throwing means and particular arrangement of the pressure areas of the valve, the valves are moved into their different operating positions in an improved and more positive manner. Other uses and advantages of the invention will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A pressure fluid motor comprising, in combination, a cylinder, a piston reciprocable in said cylinder, and fluid distribution means for said cylinder comprising means forming a valve chamber having concentric side walls and opposed end surfaces providing annular valve seats, passage means respectively adapted to conduct pressure fluid from the ends of said valve chamber to the opposite ends of said cylinder, a source of fluid under pressure, a pair of cooperating relatively movable, coaxial, fluid distributing valves reciprocably mounted in said valve chamber for controlling flow of pressure fluid from said fluid source to said passage means respectively, said valves being of the annular sleeve type and respectively having inner and outer sleeve-like bodies respectively slidingly engaging at their inner and outer peripheries the side walls of said valve chamber, said valves adapted to seat at their remote outer ends upon said annular seats, said valve bodies arranged in telescopic relation and respectively provided with annular flanges extending radially of the bodies, one an external flange at the outer periphery of the inner valve body and the other an internal flange at the inner periphery of the outer valve body, the inner valve body having its inner end movable into abutting engagement with the oppositely facing surface of the internal flange of the outer valve body in certain positions of said valves, said supply source communicating with the ends of said valve chamber exteriorly of the remote outer end surfaces of said valves, said valves when seated upon said annular seats cutting off communication of said supply source with said passage means, relatively restricted passage means con-

necting said supply source with said valve chamber between said valves for subjecting the inner end of the inner valve body and the oppositely facing surface of the internal flange of the outer valve body continuously to the action of pressure fluid, and valve-throwing passage means controlled by said piston for subjecting the inner end of the outer valve body and the oppositely facing surface of the external flange on said inner valve body to valve throwing pressure for urging said valves in relatively opposite directions toward their seats.

2. A pressure fluid motor comprising, in combination, a cylinder, a piston reciprocable in said cylinder, and fluid distribution means for said cylinder comprising means forming a valve chamber having concentric side walls and opposed end surfaces providing annular valve seats, passage means respectively adapted to conduct pressure fluid from the ends of said valve chamber to the opposite ends of said cylinder, a source of fluid under pressure, a pair of cooperating relatively movable, coaxial, fluid distributing valves reciprocably mounted in said valve chamber for controlling flow of pressure fluid from said fluid source to said passage means respectively, said valves being of the annular sleeve type and respectively having inner and outer sleeve-like bodies respectively slidingly engaging at their inner and outer peripheries the side walls of said valve chamber, said valves adapted to seat at their remote outer ends upon said annular seats, said valve bodies arranged in telescopic relation and respectively provided with annular flanges extending radially of the bodies, one an external flange at the outer periphery of the inner valve body and the other an internal flange at the inner periphery of the outer valve body, the inner valve body having its inner end movable into abutting engagement with the oppositely facing surface of the internal flange of the outer valve body in certain positions of said valves, said supply source comprising annular supply recesses communicating with the opposite ends of said valve chamber exteriorly of the remote outer ends of said valves, said valves when seated upon said annular seats cutting off communication of said supply recesses with said passage means, said supply source also including longitudinal passage means extending internally of said valve chamber between said recesses for connecting the latter in communication with each other, relatively restricted passage means for connecting said longitudinal passage means with said valve chamber within and between said valves for subjecting the inner end of the inner valve body and the oppositely facing surface of the internal flange of the outer valve body continuously to the action of pressure fluid, and valve-throwing passage means controlled by said piston for subjecting the inner end of the outer valve body and the oppositely facing surface of the external flange on said inner valve body to valve throwing pressure for urging said valves in relatively opposite directions toward their seats.

3. A pressure fluid motor comprising, in combination, a cylinder, a piston reciprocable in said cylinder, and fluid distribution means for said cylinder comprising means forming a valve chamber having concentric side walls and opposed end surfaces providing annular valve seats, passage means respectively adapted to conduct pressure fluid from the ends of said valve chamber to the opposite ends of said cylinder, a source of fluid under pressure, a pair of cooperating

relatively movable, coaxial, fluid distributing valves reciprocably mounted in said valve chamber for controlling flow of pressure fluid from said fluid source to said passage means respectively, said valves being of the annular sleeve type and respectively having inner and outer sleeve-like bodies respectively slidably engaging at their inner and outer peripheries the side walls of said valve chamber, and said valves adapted to seat at their remote outer ends upon said annular seats, said valve bodies arranged in telescopic relation and respectively provided with annular flanges extending radially of the bodies, one an external flange at the outer periphery of the inner valve body and the other an internal flange at the inner periphery of the outer valve body, the inner valve body having its inner end movable into abutting engagement with the oppositely facing surface of the internal flange of the outer valve body in certain positions of said valves, said supply source communicating with the opposite ends of said valve chamber exteriorly of the remote outer ends of said valves, said valves when seated upon said annular seats cutting off communication of said source with said passage means, relatively restricted passage means for connecting said fluid source with said valve chamber within and between said valves for subjecting the inner end of the inner valve body and the oppositely facing surface of the internal flange of the outer valve body continuously to the action of pressure fluid, and valve-throwing passage means controlled by said piston for subjecting the inner end of the outer-valve body and the oppositely facing surface of the external flange on said inner valve body to valve throwing pressure for urging said valves in relatively opposite directions toward their seats, said valve-throwing passage means comprising separate valve-throwing passages communicating with said cylinder at longitudinally spaced points and controlled by said piston for separately delivering throwing pressures respectively to the inner end of the outer valve body and the oppositely facing surface of the external flange on said inner valve body, and said valve-chamber-forming means having an annular partition for separating the points of communication of said throwing passages with said valve chamber.

4. A pressure fluid motor comprising, in combination, a cylinder, a piston reciprocable in said cylinder, and fluid distribution means for said cylinder comprising means forming a valve chamber having concentric side walls and opposed end surfaces providing annular valve seats, passage means respectively adapted to conduct pressure fluid from the ends of said valve chamber to the opposite ends of said cylinder, a source of fluid under pressure, a pair of cooperating relatively movable, coaxial, fluid distributing valves reciprocably mounted in said valve chamber for controlling flow of pressure fluid from said fluid source to said passage means respectively, said valves being of the annular sleeve type and respectively having inner and outer sleeve-like bodies respectively slidably engaging at their inner and outer peripheries the side walls of said valve chamber, said valves adapted to seat at their remote outer ends upon said annular seats, said valve bodies arranged in telescopic relation and respectively provided with annular flanges extending radially of the bodies, one an external flange at the outer periphery of the inner valve body and the other an internal flange at the inner periphery of the outer valve body, the inner

valve body having its inner end movable into abutting engagement with the oppositely facing surface of the internal flange of the outer valve body in certain positions of said valves, said supply source communicating with the opposite ends of said valve chamber exteriorly of the remote outer ends of said valves, said valves when seated upon said annular seats cutting off communication of said source with said passage means, relatively restricted passage means for connecting said fluid source with said valve chamber within and between said valves for subjecting the inner end of the inner valve body and the oppositely facing surface of the internal flange of the outer valve body continuously to the action of pressure fluid, and valve-throwing passage means controlled by said piston for subjecting the inner end of the outer-valve body and the oppositely facing surface of the external flange on said inner valve body to valve throwing pressure for urging said valves in relatively opposite directions toward their seats, said valve-throwing passage means comprising a throwing passage having communication with said cylinder at longitudinally spaced points and controlled by said piston, said throwing passage communicating with said valve chamber at a point intermediate the inner end of the outer valve body and the oppositely facing surface of the external flange of the inner valve body and adapted to conduct throwing pressure to effect concurrent urging of said valves in relatively opposite directions toward their seats.

5. A pressure fluid motor comprising, in combination, a cylinder, a piston reciprocable in said cylinder, and fluid distribution means for said cylinder comprising means forming a valve chamber having concentric side walls and opposed end surfaces providing annular valve seats, passage means respectively adapted to conduct pressure fluid from the ends of said valve chamber to the opposite ends of the cylinder, a source of fluid under pressure, a pair of cooperating relatively movable, coaxial, fluid distributing valves reciprocably mounted in said valve chamber for controlling flow of pressure fluid from said fluid source to said passage means respectively, said valves being of the annular sleeve type and respectively having inner and outer sleeve-like bodies respectively slidably engaging at their inner and outer peripheries the side walls of said valve chamber, said valves adapted to seat at their remote outer ends upon said annular seats, said valve bodies arranged in telescopic relation and respectively provided with annular flanges extending radially from the valve bodies, one an external flange at the outer periphery of the inner valve body and the other an internal flange at the inner periphery of the outer valve body, the inner valve body having spaced projections at its inner end movable into abutting engagement with an oppositely facing surface on the internal flange of the outer valve in certain positions of said valves, said supply source communicating with the ends of said valve chamber exteriorly of the remote outer ends of said valves, said valves when seated upon said annular seats cutting off communication of said supply source with said passage means, relatively restricted passage means for subjecting the inner end of the inner valve body and the oppositely facing surface on the internal flange of the outer valve continuously to the action of pressure fluid, said projections providing spaces to permit flow of pressure fluid to said valve-surfaces which are subjected

to the action of pressure fluid even when said valves are in abutting contact, and valve-throwing passage means controlled by said piston for subjecting the inner end of the outer valve body and the oppositely facing surface of the external flange on said inner valve to valve-throwing pressure for urging said valves in relatively opposite directions toward their seats.

6. A pressure fluid motor comprising, in combination, a cylinder, a piston reciprocable in said cylinder, and fluid distribution means for said cylinder comprising means forming a valve chamber having concentric side walls and opposed end surfaces providing annular valve seats, passage means respectively adapted to conduct pressure fluid from the ends of said valve chamber to the opposite ends of said cylinder, a source of fluid under pressure, a pair of cooperating relatively movable, coaxial, fluid distributing valves reciprocably mounted in said valve chamber for controlling the flow of pressure fluid from said fluid source to said passage means respectively, the outer remote ends of said valves adapted to seat upon said annular valve seats, said valves being of the annular sleeve type and having annular sleevelike bodies sealingly slidably engaging the side walls of said valve chamber and respectively provided with annular peripheral flanges extending radially of the valve bodies, one an external flange at the outer periphery of one valve body and the other an internal flange at the inner periphery of the other valve body, and said flanges at their peripheries also sealingly slidably engaging the valve chamber walls respectively, relatively restricted passage means for continuously subjecting the inner end of one valve and the oppositely facing surface on the flange of the other valve to pressure in said supply source, valve-throwing passage means controlled by said piston for subjecting the inner end of the body of said other valve and the oppositely facing surface on the flange of said one valve to valve-throwing pressures for urging said valves in relatively opposite directions toward their seats, and relatively restricted leak passages for supplying limited quantities of pressure fluid from said source to said valve surfaces which are subjected to throwing pressures.

7. A pressure fluid motor comprising, in combination, a cylinder, a piston reciprocable in said cylinder, and fluid distribution means for said cylinder comprising means forming a valve chamber, said valve chamber having alined end bores and a coaxial intermediate reduced bore, one end bore having concentric inner and outer side walls, said valve chamber having opposed end surfaces providing annular valve seats, passage means respectively adapted to conduct pressure fluid from the ends of said valve chamber to the opposite ends of said cylinder, a source of fluid under pressure, a pair of cooperating relatively movable, coaxial, fluid distributing valves reciprocably mounted in said valve chamber for controlling flow of pressure fluid from said fluid source to said passage means respectively, said valves at their outer remote ends adapted to seat upon said annular valve seats, said valves being of the annular sleeve type and having annular sleevelike bodies arranged in telescopic relation and respectively provided with annular peripheral flanges extending radially in opposite directions from said valve bodies respectively, the external peripheral surface of the body of the internally flanged valve slidably engaging the outer side wall of said one end bore and the internal pe-

ripheral surface of the body of the externally flanged valve slidably engaging the inner side wall of said one end bore, and the external peripheral surface of the body of the externally flanged valve slidably engaging the wall of said intermediate reduced bore with the exterior periphery of the external flange slidably engaging the outer wall of said other end bore, and valve-throwing passage means controlled by said piston for subjecting the inner end of the body of said internally-flanged valve and the oppositely facing surface of the external flange of said other valve to valve-throwing pressures for urging said valves in relatively opposite directions toward their seats.

8. A pressure fluid motor comprising, in combination, a cylinder, a piston reciprocable in said cylinder, and fluid distribution means for said cylinder comprising means forming a valve chamber, said valve chamber having alined end bores and a coaxial intermediate reduced bore, one end bore having concentric inner and outer side walls, said valve chamber having opposed end surfaces providing annular valve seats, passage means respectively adapted to conduct pressure fluid from the ends of said valve chamber to the opposite ends of said cylinder, a source of fluid under pressure, a pair of cooperating relatively movable, coaxial, fluid distributing valves reciprocably mounted in said valve chamber for controlling flow of pressure fluid from said fluid source to said passage means respectively, said valves at their outer remote ends adapted to seat upon said annular valve seats, said valves being of the annular sleeve type and having annular sleevelike bodies arranged in telescopic relation and respectively provided with annular peripheral flanges extending radially in opposite directions from said valve bodies respectively, the external peripheral surface of the body of the internally flanged valve slidably engaging the outer side wall of said one end bore and the internal peripheral surface of the body of the externally flanged valve slidably engaging the inner side wall of said one end bore, and the external peripheral surface of the body of the externally flanged valve slidably engaging the wall of said intermediate reduced bore with the exterior periphery of the external flange slidably engaging the outer wall of said other end bore, relatively restricted passage means for continuously subjecting the inner end of the body of the externally flanged valve and the oppositely facing surface on the internal flange of said other valve to the pressure in said fluid source, and valve-throwing passage means controlled by said piston for subjecting the inner end of the body of said internally flanged valve and the oppositely facing surface of the external flange of said other valve to valve-throwing pressures for urging said valves in relatively opposite directions toward their seats.

9. A pressure fluid motor comprising, in combination, a cylinder, a piston reciprocable in said cylinder, and fluid distribution means for said cylinder comprising means forming a valve chamber, said valve chamber having alined end bores and a coaxial intermediate reduced bore, one end bore having concentric inner and outer side walls, said valve chamber having opposed end surfaces providing annular valve seats, passage means respectively adapted to conduct pressure fluid from the ends of said valve chamber to the opposite ends of said cylinder, a source of fluid under pressure, a pair of cooperating rela-

tively movable, coaxial fluid distributing valves reciprocably mounted in said valve chamber for controlling flow of pressure fluid from said fluid source to said passage means respectively, said valves at their outer remote ends adapted to seat upon said annular valve seats, said valves being of the annular sleeve type and having annular sleeve-like bodies arranged in telescopic relation and respectively provided with annular peripheral flanges extending radially in opposite directions from said valve bodies respectively, the external peripheral surface of the body of the internally flanged valve slidably engaging the outer side wall of said one end bore and the internal peripheral surface of the body of the externally flanged valve slidably engaging the inner side wall of said one end bore, and the external peripheral surface of the body of the externally flanged valve slidably engaging the wall of said intermediate reduced bore with the exterior periphery of the external flange slidably engaging the outer wall of said other end bore, restricted passage means for continuously subjecting the inner end of the body of the externally flanged valve and the oppositely facing surface on the internal flange of said other valve to the pressure in said fluid source, valve-throwing passage means controlled by said piston for subjecting the inner end of the body of said internally flanged valve and the oppositely facing surface of the external flange of said other valve to valve-throwing pressures for urging said valves in relatively opposite directions toward their seats, and means for subjecting outwardly facing surfaces respectively at the remote outer ends of said valves to the pressure in said source and to the fluctuating pressures in said cylinder-passage means.

10. A pressure fluid motor comprising, in combination, a cylinder, a piston reciprocable in said cylinder, and fluid distribution means for said cylinder comprising means forming a valve chamber having concentric side walls, passage means respectively adapted to conduct pressure fluid from the valve chamber to the opposite ends of the cylinder, a source of fluid under pressure, a pair of cooperating relatively movable, coaxial, fluid distributing valves reciprocably mounted in said valve chamber for controlling flow of pressure fluid from said fluid source to said passage means respectively, said valves being of the annular sleeve type and respectively having annular sleeve-like bodies slidably engaging the walls of the valve chamber and respectively provided with internal and external annular flanges extending radially of the valve bodies, passage means for continuously subjecting the inner end of the body of one valve and the oppositely facing surface on the flange of the other valve to the pressure in said source, valve-throwing passage means for subjecting the inner end of the body of said other valve and the oppositely facing surface on the flange of said one valve to valve-throwing pressures, and means for subjecting outwardly facing surfaces respectively at the remote outer ends of said valves to the source-pressure and compression pressure in said cylinder passage means in opposition to the pressures on said valve surfaces which are continuously subjected to pressure.

11. A pressure fluid motor comprising, in combination, a cylinder, a piston reciprocable in said cylinder, and fluid distribution means for said cylinder comprising means forming a valve

chamber having concentric inner and outer side walls, passage means respectively adapted to conduct pressure fluid from the valve chamber to the opposite ends of said cylinder, a source of fluid under pressure, a pair of cooperating relatively movable, coaxial, fluid distributing valves arranged in said valve chamber for controlling the flow of pressure fluid from said fluid source to said passage means respectively, said valves being of the same internal and external diameters and having annular sleeve-like bodies arranged in telescopic relation, the internal and external peripheral surfaces of said valves respectively slidably engaging the concentric inner and outer side walls of said valve chamber, passage means for subjecting inwardly facing opposed surfaces on said valves respectively internally of the body of the outer valve continuously to the pressure in said source, valve-throwing passage means controlled by said piston for subjecting inwardly facing opposed surfaces on said valves respectively to valve-throwing pressures, said last mentioned opposed surfaces arranged externally of the body of the inner valve, and means for subjecting outwardly facing surfaces respectively at the remote outer ends of said valves to the source-pressure in opposition and superior to said continuous pressure.

12. A pressure fluid motor comprising, in combination, a cylinder, a piston reciprocable in said cylinder, and fluid distribution means for said cylinder comprising means forming a valve chamber having concentric inner and outer side walls, passage means respectively adapted to conduct pressure fluid from the valve chamber to the opposite ends of said cylinder, a source of fluid under pressure, a pair of cooperating relatively movable, coaxial, fluid distributing valves arranged in said valve chamber for controlling the flow of pressure fluid from said fluid source to said passage means respectively, said valves being of the same internal and external diameters and having annular sleeve-like bodies arranged in telescopic relation, the internal and external peripheral surfaces of said valves respectively slidably engaging the concentric inner and outer side walls of said valve chamber, said valves respectively having inwardly facing opposed surfaces internally of the body of the outer valve, passage means for continuously subjecting said opposed surfaces to the pressure in said source, valve-throwing passage means controlled by said piston for subjecting inwardly facing opposed surfaces on said valves respectively to valve-throwing pressures, said last mentioned opposed surfaces arranged externally of the body of the inner valve, and means for subjecting outwardly facing surfaces respectively at the remote outer ends of said valves to the source-pressure and compression pressure in said cylinder passage means in opposition to said continuous pressure.
